UNITED STATES. PATENT OFFICE.

ANDREW L. WEIS, OF MONROE, MICHIGAN, ASSIGNOR TO WEIS MANUFACTURING CO.,
OF MONROE, MICHIGAN, A CORPORATION OF MICHIGAN.

FILING DEVICE FOR TALKING-MACHINE RECORDS.

1,117,118.

Specification of Letters Patent.

Patented Nov. 10, 1914.

Application filed March 13, 1913. Serial No. 753,936.

To all whom it may concern:

Be it known that I, ANDREW L. WEIS, a citizen of the United States of America, and resident of Monroe, Monroe county, Michigan, have invented a certain new and useful Improvement in Filing Devices for Talking-Machine Records, of which the following is a specification.

My invention relates to devices for filing 10 the disk shaped records of talking machines.

Generally stated, the object of my invention is to provide a novel and highly efficient filing device for this particular purpose.

15 Special objects are to provide a device of such character that the records can be easily removed and replaced; to provide a construction whereby a filing device of this kind can be made cheaply; to provide an improved construction whereby the records will be fully inclosed and protected against dust, without danger of scratching; and to provide certain details of construction and combinations tending to increase the general 25 efficiency of a filing device of this particular character.

To these and other useful ends my invention consists in matters hereinafter set forth and claimed.

30 In the accompanying drawings: Figure 1 is a perspective of a cabinet for the envelops of a filing device embodying the principles of my invention. Fig. 2 is a cross section of a filing device embodying the principles 35 of my invention. Fig. 3 is a detail sectional view of the lower portion of said filing device. Fig. 4 is a perspective of one of the envelops, showing the side walls thereof flexed or sprung apart. Fig. 5 shows the 40 blank from which the envelop is made. Fig. 6 is a side view showing a group of the envelops laid together, illustrating the vertical series arrangement of the different number tabs thereof. Fig. 7 is a vertical section of 45 one of said envelops.

As thus illustrated, my invention comprises a cabinet A with compartments a separated by partitions a¹, the latter held together by bottom strips a² and a³, the strip a² having a rearwardly inclined upper surface. The partitions a¹ have their lower edges provided with tongues a⁴ which rest between the bottom strips. The envelops B are all alike, except that the tab b on one 55 envelop is either higher or lower than on

the adjacent envelops, there being a plurality of these vertical filing envelops in each compartment a of the cabinet. Each envelop B is closed at its rear edge b¹, and at its lower edges b² and b³, whereby each envelop is open at the top and front edges thereof. The front edges are cut away at b⁴, more on the right hand edge than on the left, to permit grasping of the disk-like record C therein. The bottom edges b² and b³ form opposite inclines for the lower edge of the record, thus holding the latter against rolling motion when seated in the envelop. Each envelop has a lower end portion b⁵ provided with a metal edged opening b⁶, and a rod D runs through all of these openings, and through the tongues a⁴, as shown in Figs. 2 and 3, the rod being held in place by a pivoted latch d at one end of the cabinet. The axis of the envelop is so located that the weight of the records tends to tilt the envelop backward upon the upper surface of the strip a², as shown in Fig. 2. Each envelop can be tilted forward to the position shown in dotted lines in Fig. 2, and in this 75 position any envelop is dependent upon friction with those at each side to hold it in position—that is, against falling backward. The tabs b, which have the numbers of the records thereon, serve as handles by which 80 the records can be pulled forward. Each envelop is made of a paper blank folded and pasted together. Thus the records can be conveniently arranged close together, and are, at the same time, easily removed without disturbing the entire collection. By removing the rod D, other envelops can be inserted in the proper compartments as fast as the collection increases, each compartment representing a letter of the alphabet. 85 Or the cabinet can be supplied in the first instance with the maximum number of envelops. By cutting away more of the right hand edge than the left, as shown in Figs. 4, 5 and 6, the insertion of the record is facilitated, as the two walls are more easily parted by the thumb of the left hand. 90

I do not limit myself to the exact construction shown and described. Also, I do not limit myself to any particular use, as it is 105 obvious that a filing device of this kind may be used for other purposes, as well as for filing records.

An important feature of my invention, it will be seen, is the tendency on the part of 110

each envelop to gravitate backward in all positions thereof. As the walls of the envelops are flexible, and as they are tightly grouped together, it follows that the insertion of the records will crowd the sides of the envelops into close frictional engagement with each other. In this way each envelop is capable of holding itself in forward position, and at the same time it tends always to gravitate in a backward direction. It is always easy, therefore, to straighten up the filing envelops of the cabinet, by running the hand along the front edges thereof, and by pushing in any envelops which have been held in their forward position. A slight jarring or rocking of the cabinet throws all of the envelops into normal position, because at no time is the center of gravity of any envelop in front of the axis thereof. No matter where the envelops are, or in what position, the center of gravity is such that they have a constant tendency to recover their normal positions.

What I claim as my invention is:

1. A filing device for talking machine disk records, comprising a cabinet, and a plurality of disk holders disposed side by side in said cabinet, each holder being in the form of an envelop having closed bottom and rear edges, and open top and front edges, said holders being mounted to oscillate about a common axis, and means for limiting the motion of the holders, serving to keep the center of gravity of each holder always behind said axis, and whereby each envelop tends to gravitate backward in all positions thereof, said means including parallel bars forming front and rear stops for said holders, each holder having a bottom portion extending downward between said bars, and said axis consisting of a removable rod extending through the said bottom portion of each holder.

2. A filing system for disk records, comprising a cabinet, a plurality of vertically disposed envelops held in said cabinet, having flexible side walls, and arranged side by side in direct contact with each other, said cabinet having means for keeping the envelops in position, but permitting some lateral expansion or displacement thereof, when the records are inserted in the envelops, and means providing a pivot for the lower end of each envelop, whereby said envelops may be tilted edgewise in the planes thereof, about a horizontally disposed axis extending through said planes, said envelops being accessible at their forward edges, at the front of the cabinet, and stops for limiting the forward and back motion of said envelops, disposed in position to keep the center of gravity of each envelop behind said axis, for all positions thereof, whereby said envelops tend to gravitate backward from their forward position, and are maintained in forward position only by friction between their sides, each envelop having closed rear and lower edges, but having open top and front edges, the upper front portion of each envelop being notched to permit grasping of the record, and said notch being deeper at one side of the record than at the other.

3. A filing system for disk records, comprising a cabinet, a plurality of vertically disposed envelops held in said cabinet, having flexible side walls, and arranged side by side in direct contact with each other, said cabinet having means for keeping the envelops in forward position only by friction between their sides.

4. A filing system for disk records, comprising a cabinet, a plurality of vertically disposed envelops held in said cabinet, having flexible side walls, and arranged side by side in direct contact with each other, said cabinet having means for keeping the envelops in position, but permitting some lateral expansion or displacement thereof, when the records are inserted in the envelops, and means providing a pivot for the lower end of each envelop, whereby said envelops may be tilted edgewise in the planes thereof, about a horizontally disposed axis extending through said planes, said envelops being accessible at their forward edges, at the front of the cabinet, and stops for limiting the forward and back motion of said envelops, disposed in position to keep the center of gravity of each envelop behind said axis, for all positions thereof, whereby said envelops tend to gravitate backward from their forward position, and are maintained in forward position only by friction between their sides, each envelop having closed rear and lower edges, but having open top and front edges, the upper front portion of each envelop being notched to permit grasping of the record, and said notch being deeper at one side of the record than at the other.

5. A filing system for disk records, comprising a cabinet, a plurality of vertically disposed envelops held in said cabinet, having flexible side walls, and arranged side by side in direct contact with each other, said cabinet having means for keeping the envelops in position, but permitting some lateral expansion or displacement thereof, when the records are inserted in the envelops, and means providing a pivot for the lower end of each envelop, whereby said envelops may be tilted edgewise in the planes thereof, about a horizontally disposed axis extending through said planes, said envelops being accessible at their forward edges, at the front of the cabinet, and stops for limiting the forward and back motion of said envelops, disposed in position to keep the center of gravity of each envelop behind said axis, for all positions thereof, whereby said envelops tend to gravitate backward from their forward position, and are maintained in forward position only by friction between their sides.

velops in position, but permitting some lateral expansion or displacement thereof, when the records are inserted in the envelops, and means providing a pivot for the lower end of each envelop, whereby said envelops may be tilted edgewise in the planes thereof, about a horizontally disposed axis extending through said planes, said envelops being accessible at their forward edges, at the front of the cabinet, and stops for limiting the forward and back motion of said envelops, disposed in position to keep the center of gravity of each envelop behind said axis, for all positions thereof, whereby said envelops tend to gravitate backward from their forward position, and are maintained in forward position only by friction between their sides, said cabinet being divided into compartments for holding said envelops in groups, and said axis being formed by a removable rod extending through the bottom of each compartment.

6. A filing system for disk records, comprising a cabinet, a plurality of vertically disposed envelops held in said cabinet, having flexible side walls, and arranged side by side in direct contact with each other, said cabinet having means for keeping the envelops in position, but permitting some lateral expansion or displacement thereof, when the records are inserted in the envelops, and means providing a pivot for the lower end of each envelop whereby said envelops may be tilted edgewise in the planes thereof, about a horizontally disposed axis extending through said planes, said envelops being accessible at their forward edges, at the front of the cabinet, and stops

for limiting the forward and back motion of said envelops, disposed in position to keep the center of gravity of each envelop behind said axis, for all positions thereof, whereby said envelops tend to gravitate backward from their forward position, and are maintained in forward position only by friction between their sides, said axis being formed by a removable rod on which said envelops are free to move sidewise.

7. A filing device for talking machine disk records, comprising a cabinet, and a plurality of disk holders disposed side by side in said cabinet, each holder being in the form of an envelop having closed bottom and rear edges, and open top and front edges, said holders being mounted to oscillate about a common axis, and means for limiting the motion of the holders, serving to keep the center of gravity of each holder always behind said axis, and whereby each envelop tends to gravitate backward in all positions thereof, said means including parallel bars forming front and rear stops for said holders, each holder having a bottom portion extending downward between said bars, and said axis consisting of a removable rod extending through the said bottom portion of each holder, said holders being flexible and having frictional contact between their sides.

Signed by me at Chicago, Illinois, this 10th day of March, 1913.

ANDREW L. WEIS.
